UNITED STATES PATENT OFFICE

152,608

DESIGN FOR A PERFUME BOTTLE

Dorothy Gibson, New York, N. Y., assignor to Dorothy Gibson Perfumes Corp., New York,
N. Y., a corporation of New York

Application September 3, 1947, Serial No. 141,180

Term of patent 3½ years

(Cl. D58—9)

To all whom it may concern:

Be it known that I, Dorothy Gibson, a citizen of the United States of America, residing at New York city, in the county of New York and State of New York, have invented a new, original, and ornamental Design for Perfume Bottle, of which the following is a specification, reference being had to the accompanying drawing, forming part thereof.

In the drawing:

Fig. 1 is a front view of a perfume bottle showing my new design;

Fig. 2 is a side view;

Fig. 3 is a top view;

Fig. 4 is a bottom view.

I claim:

The ornamental design for a perfume bottle, as shown.

DOROTHY GIBSON.
